CLAIM

The ornamental design for a vehicle tail lamp, as shown and described.

DESCRIPTION

FIG. 1 is an outer perspective view of driver side vehicle tail lamp showing our new design;

FIG. 2 is a front view thereof;

FIG. 3 is top view thereof;

FIG. 4 is bottom view thereof;

FIG. 5 is a outer perspective view of a second embodiment of the vehicle tail lamp thereof, with the vehicle tail lamp from the opposite side of the vehicle being depicted in first embodiment;

FIG. 6 is a front view thereof;

FIG. 7 is a top view thereof; and,

FIG. 8 is a bottom view.

It will be understood that the broken lines shown in the drawings illustrate portions of the vehicle tail lamp that form no part of claimed design.
